UNITED STATES PATENT OFFICE.

FRANK A. BREWER, JR., OF WATSONVILLE, CALIFORNIA.

DESIGN FOR A THREAD-CUTTER.

SPECIFICATION forming part of Design No. 34,001, dated January 29, 1901.

Application filed January 3, 1901. Serial No. 42,022. Term of patent 14 years.

To all whom it may concern:

Be it known that I, FRANK A. BREWER, Jr., a citizen of the United States, residing at Watsonville, in the county of Santa Cruz and State of California, have invented and produced a certain new and original Design for Thread-Cutters; and I do declare the following to be a full, clear, and exact description of the invention, such as will enable others skilled in the art to which it appertains to make and use the same.

The invention relates to a new and useful design for thread-cutters, which consists of the design or configuration shown in the accompanying drawings, in which—

Figure 1 is a perspective view of the thread-cutter looking from its front side, and Fig. 2 is a similar view looking from its rear side.

The leading feature of the design comprises a body portion 1, having a longitudinal slit 2, extending from one of its ends laterally toward its opposite end, an inwardly-curved upper edge 3, and fastening-prongs 4, projecting inwardly from the ends of the body portion at right angles thereto.

What I claim, and desire to secure by Letters Patent, is—

The design for a thread-cutter, as herein shown and described.

In testimony whereof I have hereunto set my hand in presence of two subscribing witnesses.

FRANK A. BREWER, JR.
